DOUBLE ARM SPOT WELDER

George D. Brent, Bloomfield, N. J., and Herbert S. Fox, Plover, Wis., assignors to Westinghouse Electric Corporation, East Pittsburgh, Pa., a corporation of Pennsylvania

Application August 30, 1952, Serial No. 307,298

8 Claims. (Cl. 219—4)

1

The present invention relates to spot welders and, more particularly, to a double arm spot welder for mounting lamp filaments.

Projector-type lamps, such as the bicycle lamp or hand lantern lamp, generally comprise a parabolical aluminized vitreous reflector having a pair of ferrules sealed into the back end, a pair of vertical filamentary lead-in conductors soldered to said ferrules, a filament welded to said conductors and a lens joined to the open end of the reflector to direct the light emitted therefrom either into a spot or flood-light beam pattern.

In the mounting or welding of the filament to the lead-in conductors, it is essential that the filament be secured in the proper location with respect to the reflector to obtain a proper light center for the lamp. For long life the welds must be uniform and strong.

In the past, the operator, employing a standard bench-type welder, would place the lamp reflector assembly in a horizontal cradle located in the bottom portion of the welder, with the filament conductors projecting vertically upward. The filaments, generally having a pair of depending supports connected and insulated from each other by a glass bead, would then be loaded in a vertical position in an upper nest above the reflector assembly. By the operation of one foot pedal, the filament would be brought downwardly and the supports aligned with the lead-in conductors of the reflector assembly in the welding position. The operator would then grasp a pair of tweezers electrodes in either hand, position them about the filament supports and lead-in conductors, and then by pressing a second pedal with her other foot she would weld both legs to the conductors simultaneously.

The welding operation required continuous operator motion and handling of the reflectors and filaments, depended largely upon the individual operator's skill, and resulted in low product subjected to high shrinkage, due to the unsatisfactory performance of the tweezers electrodes.

Hence, it has been found advantageous, according to our invention, to provide a double arm spot welder for lamp filament mounting which reduces the operator's effort and handling of the reflector assembly and filament, automatically sets the light center of the lamp, eliminates fitting or placing of the filament with respect to the reflector assembly, increases production, and reduces shrinkage. This welder consists of a pair of stationary jaws mounted on an anvil pro-

2

vided with a bead nest for automatically locating the filament position, a pair of movable electrodes insulated from each other, activated by foot action and fired automatically and successively by a welding circuit consisting of a timer, a pair of adjustable power "stats" and a pair of transformers to supply adjustable secondary current to each pair of electrodes, an adjustable locating plate, a V-block for determining automatically the light center of the lamp, and means for driving or activating the movable electrodes and timer.

To use, the operator places the filament in place in the anvil nest with the right hand and holds the reflector assembly against the locating plate and on the V-block with the left hand. Then by means of a foot pedal, the operator trips the movable jaws toward the stationary electrodes, thus successively welding, through the operation of the welding circuit first one and then the other of the filamentary supports to said lead-in conductors.

In its general aspect, the present invention has as its object the elimination of the disadvantages and defects of the prior art spot welders for mounting a lamp filament.

A specific object of the invention is to provide a double arm spot welder for lamp filament mounting which reduces the operator's effort and handling of the reflector assembly and filament, increases production, reduces shrinkage, automatically locates the lamp light center, and produces uniform strong welds free from operator variations.

Another object is to produce a double arm spot welder for lamp filament mounting, wherein the operator slides the filament into a nest with her right hand, places the reflector assembly against a light center locator plate and V-block with her left, and trips the movable electrodes by means of a foot pedal, thus automatically welding the filament supports to the lead-in conductors successively as controlled by the welding circuit.

A further object is to provide a double arm spot welder for lamp filament mounting, comprising a pair of diametrically opposed stationary electrodes mounted on an anvil carrying a filament positioning nest, a pair of movable electrodes complementary thereto, an adjustable light center locating plate and V-block for positioning the reflector assembly with respect to the nested filament, foot pedal means for tripping said movable electrodes, a welding circuit, for successively making the welds, and means for operating said movable electrodes.

Other objects of the invention will appear to those skilled in the art to which it appertains as the description thereof proceeds, both by direct recitation thereof and by implication from the context.

Referring to the accompanying drawing in which like numerals of reference indicate similar parts throughout the several views:

Fig. 1 is a plan view of a double arm spot welder embodying our invention for lamp filament mounting;

Fig. 2 is an end elevational view of the welder of Fig. 1, showing the operating mechanism for the movable electrodes and the welding circuit.

Fig. 3 is an enlarged vertical sectional view on the line III—III of Fig. 2, in the direction of the arrows, showing the upper stationary electrode and the lower movable electrode for welding a filament support to the reflector assembly lead-in conductor.

Fig. 4 is a horizontal sectional view, on the line IV—IV of Fig. 3, in the direction of the arrows, showing the lower movable electrode, lower stationary electrode, and the anvil connecting the stationary electrodes.

Fig. 5 is a vertical sectional view on the line V—V of Fig. 3 in the direction of the arrows, showing the filament supports and conductors in the welding position.

Fig. 6 is a view similar to Fig. 5, showing the reflector assembly lead-in conductors in initial position with respect to the filament supports on the anvil.

Fig. 7 is a view similar to Fig. 6 showing the position of the lead-in conductors after rotation in a clockwise direction to their final or welding position.

Fig. 8 is a vertical sectional view, on the line VIII—VIII of Fig. 1, in the direction of the arrows, showing the upper electrode shaft and associated parts.

Referring to the drawing, and particularly Figs. 1 and 2, the reference numeral 10 designates the double arm spot welder of our invention for lamp filament mounting. This welder consists essentially of a supporting frame 12 mounted on a horizontal table 14, a light center locating plate 16 on the table 14, a pair of diametrically opposed upper and lower stationary electrodes 18 and 20 secured adjacent said plate 16 on an anvil 22, a lower movable electrode 24, and an upper movable electrode 26, complementary to the stationary electrodes 18 and 20 respectively, an operating mechanism 28 for the movable electrodes 24 and 26, and a welding circuit 30. The support frame 12 when viewed from the left of Figs. 1 and 2, has a D-shaped configuration and is provided with a straight vertical support 31 near its middle portion and front and rear vertical members 34 and 33 (Fig. 1). It is mounted by means of brackets 32 to the table 14. The conventional welding circuit 30 comprises a timer and a pair of adjustable rheostats or "power stats" to provide adjustable secondary current thru a pair of transformers to the electrodes.

Locating plate

The light center locating plate 16, shown particularly in Fig. 2, consists essentially of a vertical plate-like member 35 provided with a lead-in conductor clearance hole 36 in its upper end and an adjustable positioning stop 36' located on its right side. Member 35 is also provided with a V-block as hereinafter described which is formed

to fit the outer contour of a parabolic aluminized reflector 37 of a reflector assembly 38.

The assembly 38, shown in section in Fig. 4 comprises the reflector 37 provided with a pair of outer ferrules 40 and 41, an exhaust tubulation 42, a pair of angular lead-in conductors 44 and 46 which are soldered to the ferrules 40 and 41 and a positioning lip 47 on its outer periphery for cooperation with the stop 36' on member 35.

The member 35 has on its loading side a V-block having elements 48 and 50 (Fig. 2) which extend angularly upwards from a body portion 52. The blocks are adjustable vertically with respect to member 35 by means of a pair of vertical slots in body portion 52. The member 35 is in turn fastened, as by bolts extending through the body portion 52, to a slide plate 54 adjustably mounted on a slide 56 on the table 14.

Anvil and stationary electrodes

Adjacent the locating plate 16, opposite its loading side, the anvil 22 having a circular filament loading station platform 58 (Fig. 1), as an extension thereof is adjustably mounted on a bracket 57 adjacent plate 35. This bracket 57 is adjustably secured and slideable on the plate 56. This anvil 22 has an axial "nest" cavity 62 of rectangular cross section at its forward end adjacent the plate 16 in which is mounted, by means of volts, a filament button "nest" 64 (Figs. 3 and 4) for automatically positioning a filament assembly 66 with respect to the reflector assembly 38.

The filament assembly 66 consists of a pair of angular filament supports 68 and 70 (Fig. 4) with horizontal extremities positioned transverse to the extremities of conductors 44 and 46. The supports are mounted with respect to, and insulated from, each other by a vitreous button 72 which is accurately located with respect to a filament 74 mounted on the light-source ends of the supports 68 and 70. The "nest" 64 has an axial button-positioning slot 75 in the end adjacent plate 16, thus automatically positioning filament 74 at the light center of the reflector assembly 38.

As shown particularly in Fig. 2, the upper stationary electrode 18 is mounted by means of a bracket or electrode-mounting arm 76 (Fig. 3) above and forward of the anvil 22. The underside of the anvil 22 directly beneath the bracket or arm 76 is suitably cut away to permit the passage therethrough of the lower movable electrode 24 for engagement with the stationary electrode 18. As also shown in Fig. 2, the opposed lower stationary electrode 20 is similarly mounted on the anvil 22 by bracket 78.

It will be understood that the aforementioned filament loading platform 58, or continuation of the anvil 22, merely provides convenient filament assembly storing space for easy movement of the filament assembly 66 into the "nest" 64 for filament mounting.

Movable electrodes

The lower movable electrode 24, which cooperates with the stationary electrode 18 (Figs. 1 and 2), is rotatably secured on the welding end of a lower electrode arm 80 having its other end journaled on a lower electrode arm shaft 82 on the frame 12. The upper movable electrode 26 is similarly carried on one end of an upper electrode arm 84 journaled on an upper electrode shaft 86. The upper shaft 86, as shown in Fig. 1, extends through both sides 33 and 34 and the

support 31 of the frame 12 and through suitable bushings located therein, whereas the lower shaft 82 extends through the front side wall 34 and support 31 of frame 12 and is mounted on bushings therein.

Operating mechanism

The operating mechanism 28 for the movable electrodes 20 and 22 and the welding circuit 30 has in addition to the shafts 82 and 86 and the arms 80 and 84 a bell crank lever 92 (Figs. 2 and 8) which is journalled on the shaft 86 between the support 31 and rear end portion 33 (Fig. 1) of the frame 12. This lever 92 (Fig. 8) has a lever spring anchor arm 94 adjacent the brackets 32, and a downwardly depending cam arm 96 which carries a horizontal cam mounting plate 98 located intermediate the ends of the arm 96. This plate 98 carries a timer cam 100 adjustable by means of bolts extending through slots therein.

Adjacent the cam 100, a pivotable timer cam follower 102 carrying a roller 104 for engagement with the timer cam 100, is pivotally mounted on a shaft 106 (Fig. 1) which is secured in suitable brackets depending from the rearward side of the frame 12. The underside of the timer cam follower 102 rests on a microswitch rod 108 vertically reciprocable thereby in a bushing 110 (Fig. 2) on the table 14. This rod 108, when it is moved downwardly by the cam follower 102, closes the welding circuit (indicated by a block diagram in Fig. 2) and causes the timer to energize the transformers thru the adjustable "power stats" thus welding first the support 68 to the lead-in conductor 44, both positioned between the upper stationary jaw 18 and the lower movable electrode 24, and then the other filament support 70 to the lead-in conductor 46 held between the upper movable electrode 26 and the lower stationary electrode 20.

The lower end of the cam arm 96 of the bell crank lever 92 is secured to a foot pedal cable 112 which extends over a pulley 114, Figs. 1 and 2, mounted on one of the frame brackets 32 and attached to a suitable foot pedal (not shown) on the floor beneath the table 14.

As shown in Figs. 1, 2, and 8, a bell crank drive arm 116 is fixed adjacent lever 92 to the upper shaft 86, as by means of a set screw 117, and depends downwardly therefrom adjacent the upper portion of the cam mounting plate 98. The lower end of the arm 116 is provided with a horizontal pin 118 (Fig. 1) which engages the cam arm 96, moving for a limited distance, with the bell crank lever 92, as the shaft 86 is rotated in a clockwise direction.

Between the bell crank lever 92 and support 31 of the frame 12, spring anchor arm 120 is also affixed to the shaft 86 as by a suitable set screw 121. The outer end of the arm 120 is joined by means of a tension spring 122 (Figs. 1 and 2) to the spring anchor arm 94 of the bell crank lever 92.

Between arm 120 and the front side member 34 of the frame 12, an upper electrode tensioning arm 124 carrying on its outer extremity a spring pin 128 (Figs. 1 and 2) is also fixed to the shaft 86. A tension spring 130 extends from an adjustable hook 132 (Fig. 2) in the upper electrode tensioning arm 84 to the spring pin 128.

The upper electrode arm 84, as hereinbefore mentioned, is journalled on the shaft 86 between arm 124 and the front side frame member 34.

A suitable electrical connection 134 is provided on the shaft end of the arm 84. As shown in Fig. 1 adjacent the upper arm 84, a drive gear 136 is fixed to the shaft 86. On the other end 5 of the shaft 86 a shaft-biasing torsion spring 140 (Fig. 1) is provided between the vertical side member 33 of the frame 12 and a suitable collar 142 fixed to said shaft.

As shown particularly in Fig. 2, the drive gear 136 engages a driven gear 144 on the lower shaft 82. The lower electrode arm 80 is journalled on the shaft 82, suitably directly beneath the upper electrode arm 84 on the shaft 86. Between the gear 144 and the lower arm 80 a lower electrode 15 drive arm 146 having on its outer end an electrically insulated horizontal pin 148 extending into the lower arm 80 is fixed to the lower shaft 82. A suitable electrical connection 150, shown in Fig. 2, is provided on the lower electrode arm 20 80.

Operation

To load the double arm spot welder 10 of our invention, the operator moves a filament assembly 68 from the loading platform 58, by hand 25 or with tweezers, into position on the anvil "nest" 64 (Fig. 4), so that the top of the button 72 rests against the inner portion of the button-positioning slot 75. With her left hand, the operator 30 holds the reflector assembly 38 against the locating plate 16, resting the bottom portion of the reflector 37 on the V-block elements 48 and 50. The lead-in conductors 44 and 46 are inserted at an angle with respect to the horizontal portions 35 of the filament supports 68 and 70, as shown in Fig. 6, so that the conductor 44 is beneath support 68 and conductor 46 is above support 70. The assembly 38, and particularly the part comprising the inner extremities of the conductors 44 and 70, is rotated clockwise until the lip 47 of reflector 37 strikes stop 36' on member 35 (Fig. 5) thus positioning the conductors 68 and 70 to make contact with the supports 44 and 46, respectively, as shown in Fig. 7.

With her foot the operator depresses a pedal, (not shown) thus moving the bell crank lever 92 (Fig. 2) in a clockwise direction. The clockwise swinging of the lever 92 and the spring anchor arm 94 thereon resiliently rotates the shaft 86 clockwise by means of the spring 122 and spring anchor arm 120. Rotation of the shaft 86 causes the bell crank drive arm 116, upper electrode tensioning arm 124 and hence, by means of the spring 130 (connecting arm 124 to upper arm 84), the arm 84 clockwise and upper movable electrode 26 to move into contact with the work namely conductor 46 and support 70 on lower jaw 20. Continued foot pressure by the operator causes lever 92 to rotate further, thereby applying pressure to the work. It will be understood that after electrode 26 contacts the work the horizontal pin 118 (Figs. 1 and 8) breaks contact with the lever arm 96, and the shaft 86 ceases its rotation.

65 Simultaneously, the driven gear 144 on lower shaft 82 is rotated counterclockwise by means of drive gear 136 on the upper shaft 86. The arm 146 on shaft 82 and hence the lower welding electrode arm 80, which is pinned to arm 146, are also rotated counterclockwise. The lower movable electrode 22 on arm 80 moves upwardly into contact with the work namely support 72 and conductor 44 on the upper stationary electrode 18.

It will be also understood that the clockwise 70 rotation of the bell crank lever 92 has caused

the roller 104 on the end of the cam follower 102 to roll over the cam 100 secured to the cam plate 98 on the bell crank lever depending arm 96, thus moving the timer rod 108 downwardly to successively pass current through first one and then the other transformer in the welding circuit 30. Secondary current from the transformers successively passes thru stationary electrode 18, the work, and movable electrode 24 and then stationary electrode 20, the work, and upper movable electrode 26, thus welding in succession filament support 68 to conductor 44 and support 70 to conductor 46.

As the operator releases the foot pressure on the pedal, (now shown) the torsion spring 140 on the rearward end (Fig. 1) of the upper shaft 86 returns the upper shaft 86, the lower shaft 82 and the associated parts thereon to their normal or starting position. The operator then removes the reflector assembly 38, having the filament assembly 66 mounted thereon, from the locating plate 16 of the double arm spot welder 10.

Although a preferred embodiment of our invention has been disclosed, it will be understood that modifications may be made within the spirit and scope of the invention.

We claim:

1. A double arm spot welder for mounting a lamp filament assembly having a pair of filament supports, a filament mounted on said supports and a vitreous button for supporting and insulating said supports and locating said filament with respect thereto, on a reflector assembly having a reflector and a pair of lead-in conductors mounted thereon, comprising a frame, an adjustable anvil mounted on said frame, on said anvil a filament button nest for positioning said filament assembly at the light center of said reflector assembly, and a pair of diametrically opposed upper and lower stationary electrodes about said nest, a pair of diametrically opposed lower and upper movable electrodes for cooperating with said stationary electrodes to weld successively one filament support to one conductor and then the other support to the other conductor, an adjustable light center locating plate on said frame adjacent said anvil for positioning said reflector assembly with respect to a filament nested on said anvil, a welding circuit for successively making said pair of welds, and an operating mechanism on said frame for tripping said movable electrodes onto said pair of filament supports and conductors supported on said lower stationary electrode and said nest and energizing said welding circuit to perform said welds.

2. A double arm spot welder for mounting a lamp filament assembly having a pair of filament supports, a filament mounted on said supports and a vitreous button for supporting and insulating said supports and locating said filament with respect thereto, on a reflector assembly having a reflector and a pair of lead-in conductors mounted thereon, comprising a frame, an adjustable anvil mounted on said frame, on said anvil a filament button nest for positioning said filament assembly at the light center of said reflector assembly, and a pair of diametrically opposed upper and lower stationary electrodes about said nest, a pair of diametrically opposed lower and upper movable electrodes for cooperating with said stationary electrodes to weld successively one filament support to one conductor and then the other support to the other conductor, an adjustable light center locating plate on said frame adjacent said anvil for positioning said

reflector assembly with respect to a filament nested on said anvil, said light center locating plate comprising a vertical plate-like member provided with a conductor clearance hole in its upper end and a V-block formed to fit the outer contour of said reflector, said V-block having a body portion and elements extending angularly upwards from said body portion thereof, a sliding plate for mounting said body portion and a slide for supporting said plate, a welding circuit for successively making said pair of welds, and an operating mechanism on said frame for tripping said movable electrodes onto said pair of filament supports and conductors supported on said lower stationary electrode and said nest and energizing said welding circuit to perform said welds.

3. A double arm spot welder for mounting a lamp filament assembly having a pair of filament supports, a filament mounted on said supports and a vitreous button for supporting and insulating said supports and locating said filament with respect thereto, on a reflector assembly having a reflector and a pair of lead-in conductors mounted thereon, comprising a frame, an adjustable anvil mounted on said frame, on said anvil a filament button nest for positioning said filament assembly at the light center of said reflector assembly, and a pair of diametrically opposed upper and lower stationary electrodes about said nest, a pair of diametrically opposed lower and upper movable electrodes for cooperating with said stationary electrodes to weld successively one filament support to one conductor and then the other support to the other conductor, an adjustable light center locating plate on said frame adjacent said anvil for positioning said reflector assembly with respect to a filament nested on said anvil, a welding circuit for successively making said pair of welds, said welding circuit comprising a timer, a pair of adjustable power stats for controlling the current to said pairs of electrodes, a pair of transformers for successively supplying said pairs of electrodes with adjustable secondary current during the welding cycle as determined by said timer and cam operated means for mechanically energizing said timer, said means comprising a reciprocable rod and a cam follower for engagement with said rod and having a roller for engagement with said timer cam, and an operating mechanism on said frame for tripping said movable electrodes onto said pair of filament supports and conductors supported on said lower stationary electrode and said nest and energizing said welding circuit to perform said welds.

4. A double arm spot welder for mounting a lamp filament assembly having a pair of filament supports, a filament mounted on said supports and a vitreous button for supporting and insulating said supports and locating said filament with respect thereto, on a reflector assembly having a reflector and a pair of lead-in conductors mounted thereon, comprising a frame, an adjustable anvil mounted on said frame, on said anvil a filament button nest for positioning said filament assembly at the light center of said reflector assembly, and a pair of diametrically opposed upper and lower stationary electrodes about said nest, a pair of diametrically opposed lower and upper movable electrodes for cooperating with said stationary electrodes to weld successively one filament support to one conductor and then the other support to the other conductor, an adjustable light center locating plate

on said frame adjacent said anvil for positioning said reflector assembly with respect to a filament nested on said anvil, a welding circuit for successively making said pair of welds, and an operating mechanism on said frame for tripping said movable electrodes onto said pair of filament supports and conductors supported on said lower stationary electrode and said nest and energizing said welding circuit to perform said welds, said operating mechanism comprising on said frame an upper welding arm shaft, and a lower welding arm shaft connected to said upper shaft by means of gears, on said upper shaft a bell crank lever, a bell crank lever drive arm carrying a pin for engagement with said lever, an upper welding electrode tensioning arm, an upper electrode welding arm, a spring anchor arm, and a torsion spring for returning said upper shaft to its normal position, said bell crank lever comprising a lever spring anchor arm and a downwardly depending cam arm, said cam arm having thereon a horizontal cam mounting plate provided with an adjustable timer cam and means for connecting said cam arm with welder driving means, on said lower shaft, a lower welding electrode arm and a lower electrode drive arm connected to and insulated from said lower electrode arm, spring means for connecting said lever spring anchor arm to said spring anchor arm, and spring means for connecting said upper electrode tensioning arm to said upper electrode arm.

5. A double arm spot welder for mounting a lamp filament assembly having a pair of filament supports, a filament mounted on said supports and a vitreous button for supporting and insulating said supports and locating said filament with respect thereto, on a reflector assembly having a reflector and a pair of lead-in conductors mounted on said frame, on said anvil a filament button nest for positioning said filament assembly at the light center of said reflector assembly, and a pair of diametrically opposed upper and lower stationary electrodes about said nest, a pair of diametrically opposed lower and upper movable electrodes for cooperating with said stationary electrodes to weld successively one filament support to one conductor and then the other support to the other conductor, an adjustable light center locating plate on said frame adjacent said anvil for positioning said reflector assembly with respect to a filament nested on said anvil, said light center locating plate comprising a vertical plate-like member provided with a conductor clearance hole in its upper end and a V-block formed to fit the outer contour of said reflector, said V-block having a body portion and elements extending angularly upwards from said body portion thereof, a sliding plate for mounting said body portion and a slide for supporting said plate, a welding circuit for successively making said pair of welds, said welding circuit comprising a timer, a pair of adjustable power stats for controlling the current to said pairs of electrodes, a pair of transformers for successively supplying said pairs of electrodes with adjustable secondary current during the welding cycle as determined by said timer and cam operated means for mechanically energizing said timer, said means comprising a reciprocable rod and a cam follower for engagement with said timer cam, and an operating mechanism on said frame for tripping said movable electrodes onto said pair of filament supports and conductors supported on said lower stationary electrode and said nest and energizing said

welding circuit to perform said welds, said operating mechanism comprising on said frame an upper welding arm shaft, and a lower welding arm shaft connected to said upper shaft by means of gears, on said upper shaft a bell crank lever, a bell crank lever drive arm carrying a pin for engagement with said lever, an upper welding electrode tensioning arm, an upper electrode welding arm, a spring anchor arm, and a torsion spring for returning said upper shaft to its normal position, said bell crank lever comprising a lever spring anchor arm and a downwardly depending cam arm, said cam arm having thereon a horizontal cam mounting plate provided with an adjustable timer cam and means for connecting said cam arm with welder driving means, on said lower shaft, a lower welding electrode arm and a lower electrode drive arm connected to and insulated from said lower electrode arm, spring means for connecting said lever spring anchor arm to said spring anchor arm, and spring means for connecting said upper electrode tensioning arm to said upper electrode arm.

6. A light center locating plate for a double arm spot welder for welding the filament supports of a filament assembly to the lead-in conductors of a reflector comprising a vertical plate-like member provided with a conductor clearance hole in its upper end and a V-block formed to fit the outer contour of said reflector, said V-block having a body portion and elements extending angularly upwards from said body portion thereof, a sliding plate for mounting said body portion and a slide for supporting said plate.

7. An operating mechanism for the movable electrodes of a double arm spot welder for lamp filament mounting comprising a frame, on said frame an upper welding arm shaft, and a lower welding arm shaft connected to said upper shaft by means of gears, on said upper shaft, a bell crank lever, a bell crank lever drive arm carrying a pin for engagement with said lever, an upper welding electrode tensioning arm, an upper electrode welding arm, a spring anchor arm, and a torsion spring for returning said upper shaft to its normal position, said bell crank lever comprising a lever spring anchor arm and a downwardly depending cam arm, said cam arm having thereon a horizontal cam mounting plate provided with an adjustable timer cam and means for connecting said cam arm with welder driving means, on said lower shaft, a lower welding electrode arm and a lower electrode drive arm connected to and insulated from said lower electrode arm, spring means for connecting said lever spring anchor arm to said spring anchor arm, and spring means for connecting said upper electrode tensioning arm to said upper electrode arm.

8. An anvil for a double arm spot welder for mounting a lamp filament assembly having a pair of filament supports, a filament mounted thereon, and a vitreous button for supporting and insulating said supports, and locating said filament with respect thereto, provided with an axial forward nesting cavity and having a filament button nest in said cavity, a filament loading station platform extension at the rear of said anvil, an upper stationary welding electrode mounted on one side of said anvil, a stationary lower electrode mounted on the other side of said anvil, and means for mounting said anvil adjustable in a vertical and horizontal direction.
